UNITED STATES PATENT OFFICE

WILLIAM E. PABST, OF ANDERSON, INDIANA, ASSIGNOR TO DELCO-REMY CORPORATION,
OF DAYTON, OHIO, A CORPORATION OF DELAWARE

APPARATUS FOR REMOVING COMMUTATORS FROM ARMATURE SHAFTS

Application filed November 29, 1927. Serial No. 236,460.

This invention relates to the manufacture of armatures for dynamo electric machines, and particularly to the type of manufacture in which an armature core is first assembled upon a shaft, windings are assembled on the armature core, a previously formed commutator is press-fitted on the shaft, and the leads of the armature conductors are attached to the commutator segments.

10 One object of the present invention is to provide apparatus for quickly removing the commutator from an assembled armature. The apparatus is particularly useful in case the armature has been found defective because of short circuit and must be disassembled.

Further objects and advantages of the present invention will be apparent from the following description, reference being had to 20 the accompanying drawings, wherein a preferred form of embodiment of the present invention is clearly shown.

In the drawings:

Fig. 1 is a side elevation of a commutator 25 removing device embodying the present invention.

Fig. 2 is a sectional view on a larger scale taken principally on the line 2—2 of Fig. 1.

Fig. 3 is a sectional view on the line 3—3 of 30 Fig. 2.

Fig. 4 is a sectional view similar to Fig. 2 showing the position of the apparatus after the commutator has been stripped from the armature shaft.

Fig. 5 is a plan view looking in the direction of the arrow 5 of Figs. 1 and 4.

The apparatus comprises mainly a device for supporting an assembled armature and for providing for its longitudinal movement, 40 means for gripping the commutator and holding it stationary while the assembly of armature shaft, core and winding is being moved endwise and means engageable with the end of the armature shaft for moving the same relative to the commutator so that the commutator may be stripped from the shaft. In the disclosed form of the present invention the last named means is a plunger operated by an arbor press which comprises a 45 frame 20 providing a base 21 and a tubular

guide 22 which guides a rack 23 cooperating with a gear 24 attached to a shaft 25 operated by a handle 26. The rack 23 carries a plunger 27 for engaging the upper end of an armature shaft 28 upon which are assembled a core 29, windings 30, and a commutator 31. The armature assembly is received by a recess 32 in a block 33 which supports for vertically sliding movement a plate 34 having extensions 35 and 36 received by channels 37 and 38 respectively provided by the block 33. The plate 34 is provided with a notch 39 for receiving the lower end of the armature shaft 28. The plate 34 is supported by springs 40 resting at their lower ends in tubes 41 which are fastened to a plate 42 which, together with a base 43 and blocks 44 and 45 are secured to the block 33 by bolts 46. The upper ends of the springs 40 are located by being placed around lugs 47 provided by the plate 34.

The means for gripping the commutator and holding it stationary while the shaft is moved downwardly comprises gripping jaws 50 having teeth 51 pointing upwardly and having shanks 52 which are guided for vertical and horizontal movement by channels 53 provided in the block 33. These channels are covered by cover-plates 54. The shanks 52 are attached to rods 55 which extend through holes 56 in the plate 34 and which are threaded at their lower ends to receive nuts 57 which support springs 58, located between the nuts 57 and the plate 34. The gripping jaws 50 are provided with inclined camming surfaces 60 which are engaged by corresponding camming surfaces 61 of the plates 54.

To use the apparatus the operator will place an armature assembly upon the plate 34 as shown in Fig. 2. As the plunger 27 of the arbor press is lowered by turning the handle 26 clockwise as viewed in Fig. 1 the plate 34 which supports the armature assembly will move downwardly compressing the springs 40 and transmitting downward motion through the springs 58 to the gripping jaws 50. As the gripping jaws 50 move downwardly they will be cammed inwardly toward the commutator 31 due to the cooperation of the surfaces 60 and 61. The tend-

ency of the commutator 31 to move downwardly will cause it to be gripped on opposite sides by the teeth 51. Therefore, the commutator 31 will be firmly gripped between gripping jaws 50 and will be prevented from moving downwardly while the remainder of the armature assembly is moved into the position shown in Fig. 4. During the movement of the plate 34 into this position its extensions 35 and 36 will engage latches 65 and 66, respectively, which are slidable through recesses 67 and 58 respectively, provided by the plate 45. Springs 69 yieldingly urge these latches inwardly, and inward movement of each of the latches is resisted by stop pin 70 which extends through slot 71 provided by the plate 45.

After the plate 34 is moved into the position shown in Fig. 4 the latches 65 and 66 will retain the plate so that the operator may withdraw the armature assembly from which the commutator has stripped. To restore the apparatus to the position shown in Figs. 1 and 2 the pins 70 are moved away from the central part of the apparatus by operating levers 72 which are pivotally supported by the plate 45 and are adapted each to engage one of the pins 70. When the levers 72 have been moved sufficiently to retract the latches 65 and 66 from the plate 34, the springs 40 will be released to move the plate 34 to the position shown in Fig. 2, whereupon the compression of the springs 58 will be relieved and the gripping jaws 50 may be separated from the commutator 51.

The commutator 51 may be used again if not defective. The short circuited armature may be stripped of its windings and the core may be rewound.

While the form of embodiment of the present invention as herein disclosed, constitutes a preferred form, it is to be understood that other forms might be adopted, all coming within the scope of the claims which follow.

What is claimed is as follows:

1. Apparatus for removing a commutator from an armature shaft carrying a core and a commutator, comprising in combination, a device for supporting the shaft assembly, means for engaging the end of the shaft to move it endwise, and means for gripping the commutator and preventing it from moving endwise as the remainder of the assembly is moved.

2. Apparatus for removing a commutator from an armature shaft carrying a core and a commutator, comprising in combination, a device for supporting the shaft assembly, and means for engaging the end of the shaft to move it endwise, and means actuated in response to movement of the shaft endwise for gripping the commutator and preventing endwise movement thereof as the remainder of the assembly is moved.

3. Apparatus for removing a commutator

from an armature shaft carrying a core and a commutator, comprising in combination, a plate for supporting the shaft assembly for vertical movement, a vertically movable rod for engaging the upper end of the shaft to move it downwardly and means actuated in response to downward movement of the plate for gripping the commutator and preventing downward movement thereof as the remainder of the assembly is moved downwardly.

4. Apparatus according to claim 3 in which the plate is supported on springs which tend to restore the plate to uppermost position.

5. Apparatus according to claim 3 in which the plate is supported on springs which tend to restore the plate to uppermost position, and in which means are provided for latching the plate in lowermost position to facilitate removal of the shaft and core from the apparatus after the commutator has been removed.

6. Apparatus according to claim 3 in which gripping jaws are provided for engaging the commutator, and in which commutator engaging movement of the jaws is imparted to them in response to downward movement of the plate.

7. Apparatus for removing a commutator from an armature shaft carrying a core and a commutator, comprising in combination, a movable plate for supporting the shaft assembly for vertical movement, a vertically movable rod for engaging the shaft to move it and the plate downwardly, gripping jaws, means for guiding said gripping jaws horizontally and vertically, means actuated by the plate for moving said jaws vertically, and cam means for causing said jaws to move into engagement with and hold the commutator as the jaws are moved vertically.

8. Apparatus for removing a commutator from an armature shaft carrying a core and a commutator, comprising in combination, a movable support, resiliently supported, for supporting the shaft assembly, means for engaging the end of the shaft to move it endwise, gripping jaws to grip the commutator, guiding means for said jaws, comprising a slot and a cam, and resilient means actuated by said plate for causing said jaws to engage said commutator.

9. Apparatus for removing a commutator from an armature shaft carrying a core and a commutator, comprising in combination, means for engaging the end of the shaft to move it endwise and means actuated in response to movement of the shaft endwise for gripping the commutator and preventing endwise movement thereof as the remainder of the assembly is moved.

In testimony whereof I hereto affix my signature.

WILLIAM E. PABST.
